UNITED STATES PATENT OFFICE.

WILLIAM ANDERSON BLACK, OF WEST ASHEVILLE, NORTH CAROLINA.

THERMOMETER-CASE.

1,333,601.

Specification of Letters Patent. Patented Mar. 16, 1920.

Application filed June 4, 1919. Serial No. 301,692.

To all whom it may concern:

Be it known that I, WILLIAM A. BLACK, citizen of the United States, residing at West Asheville, in the county of Buncombe and State of North Carolina, have invented certain new and useful Improvements in Thermometer-Cases, of which the following is a specification.

This invention relates to surgical accessories, and more particularly to an improvement in instrument cases especially adapted for carrying thermometers.

The relatively fragile and delicate nature of physicians' thermometers is well known, and not only is it desirable to provide safe and practical means for carrying the same, but to also facilitate reducing the column of mercury therein to normal after it has been used. Frequently, great difficulty is experienced in successfully performing the latter operation, owing to the fact that it is difficult to obtain a good grip on the thermometer in conjunction with the snapping wrist movement usually necessary to give the same a sufficient jar to bring the mercury back to its normal condition. Furthermore, in addition to the hazard of the thermometer slipping from the hand in the mercury resetting operation it is likely to strike against an obstruction which will cause it to be broken. Having these difficulties in view the present invention aims to provide a simple and practical case which may be conveniently carried in the pocket or physician's valise to protect the thermometer while thus being transported, and also while still held in the protecting sheath or case may be subjected to sufficient jar to reduce the mercury as desired.

Accordingly, a primary object of the invention is to provide a device which acts as a protecting case and is also provided with means whereby the thermometer carrying portion of the device may be readily manipulated to obtain the desired shock or jar for resetting, while thoroughly protected.

A further object of the invention is to provide a casing which may be made in an economical manner, and by reason of its simple construction may be readily manipulated to obtain the desired result in a thoroughly satisfactory manner.

With the above and other objects in view which will more readily appear as the nature of the invention is better understood,

the same consists in the novel construction, combination and arrangement of parts hereinabove more fully described, illustrated and claimed.

A preferred and practical embodiment of the invention is shown in the accompanying drawings, in which:—

Figure 1 is a perspective view of the casing forming the subject matter of the present invention.

Fig. 2 is a perspective view thereof illustrating the manner of manipulating the same for the purpose of resetting or reducing the mercury column.

Fig. 3 is a side elevation thereof.

Fig. 4 is a cross sectional view taken on the line 4—4 of Fig. 3.

Similar reference characters designate corresponding parts throughout the several figures of the drawings.

In carrying the present invention into effect it is proposed to utilize any material suitable and available for that purpose, such for instance as leather, hard rubber or metal. As shown in the drawings the present invention essentially comprises a relatively rigid thermometer carrier having body portion 1 of elongated formation which has fitted to one face thereof a suitable sheath or casing part 2 which provides a pocket for receiving the thermometer T, while the end thereof adjacent the entrance to the casing 2 is provided with a flap which is adapted to fold over on to the body 1 in such a manner as to form additional protection for the thermometer carried within the casing part 2.

The said flap 3 essentially consists of a relatively stiff or rigid body portion 4 and a flexible web portion 5 for connecting the stiffened or rigid portion of the flap with the similar part 1 of the thermometer carrier. As previously indicated when the flap 3 is folded toward the side of the thermometer carrier base on which the pocket 2 is provided, it provides for thoroughly protecting the thermometer from breakage and gives added strength and reinforcement to the entire device, and in order to provide a more compact device, and also more adequately protect the thermometer, the inside face of the relatively stiff or rigid part 4 of the flap may be provided with a groove or depression 6 as shown in Figs. 3 and 4, whereby the thermometer may nest within

the groove and have the function of holding the flap and base against relative lateral or sidewise slipping.

In addition to this protecting feature of the flap 3 the rigid portion 4 constitutes a handle whereby the device may be readily manipulated to subject the party carrying the thermometer to a shock or jar which will reset the mercury of the thermometer carried in the pocket 2. That is to say, one of the novel and distinctive features of the present invention is the flap 3 which consists of the relatively rigid and flexible parts 4 and 5 whereby the thermometer carrying base 1 connected to the web 5 will be subjected to a sudden jar when the handle portion of the flap is held in the hand of the operator and given a sharp downward thrust.

20. The manner of manipulating the casing to effect the desired result is illustrated in Fig. 2 wherein the dotted lines show how the rigid portion 4 of the flap may be gripped by the hand with the thumb and forefinger gripping the flexible part 5 between the two relatively rigid or stiff members so that the thermometer carrying part may have a free swinging movement through an arc of a circle, and when 25 abruptly stopped will produce a sufficient shock or jar to lower the column of mercury in the thermometer. At the start of the operation the thermometer carrying part 1 will occupy substantially the position indicated by the dotted line *a*, and upon downward movement of the hand the part 1 will move in the direction of the arrow to the several dotted line positions indicated until it reaches the position indicated by the dotted line *b* where the reducing shock or jar takes place. Thus the operation of reducing the mercury to its normal position involves substantially the same action as snapping a whip, as the casing is held by the hand and the arm given a movement similar to that involved in such action.

From the foregoing it will be apparent that the present invention contemplates a simple and practical device which performs 50 the dual function of a protector for the thermometer and at the same time affords means for readily manipulating the casing to quickly and safely reduce the mercury column. And, while various changes of ma-

55 terial and design may be resorted to in different commercial embodiments of the invention, nevertheless the essential features of the thermometer carrying base and a relatively rigid flap which constitutes a combined protector and manipulating handle 60 are adhered to. That is to say, while the form of invention shown in the accompanying drawing is a preferred embodiment thereof, it will of course be understood that various changes in the form, proportion and 65 minor details of construction may be resorted to without departing from the spirit of the invention or scope of the appended claims.

70 I claim:—

1. A thermometer case consisting of a pair of members connected by a flexible intermediate web portion whereby they may be folded toward each other into registering relation, and means carried by the inner face 75 of one of said relatively rigid members for housing a thermometer whereby the same will be located between both members when the same are in folded position.

2. A thermometer case consisting of a pair 80 of members connected by a flexible intermediate web portion, and a casing secured to one of said members and providing a thermometer receiving pocket having its open end disposed adjacent the flexible web.

85 3. A thermometer case including a thermometer carrying base formed with a thermometer receiving pocket, and a flap including a relatively rigid part and a flexible part connected with the thermometer carrying base, and said relatively rigid part of the flap being provided with a groove on its inner face whereby the thermometer casing may nest therein when the flap is folded on to the body.

90 4. A thermometer case including a thermometer carrying base, and a combined manipulating handle and protecting flap hingedly connected with said base whereby the same may be folded into protecting relation 100 with reference to the thermometer carried by the base.

In testimony whereof I hereunto affix my signature in the presence of two witnesses.

WILLIAM ANDERSON BLACK.
